UNITED STATES PATENT OFFICE.

BERNARD W. JAPS, OF MINNEAPOLIS, MINNESOTA.

LOOSE-LEAF BINDER.

Application filed April 17, 1926. Serial No. 102,705.

This invention relates to improvements in loose leaf binders and more particularly to the locking means therefor.

An object of the invention is to provide a loose leaf binder of simple inexpensive construction comprising a bar having spaced posts secured thereto and adapted to receive a similarly shaped hollow member having a locking means mounted therein and operable 10 exteriorly of the member for securing it to the posts in adjusted positions.

A further object of the invention is to provide a loose leaf locking device comprising a member having normally expanded 15 clamping sleeves mounted therein adapted to receive a pair of posts mounted in a complementary bar, said member having means mounted therein and engageable with the sleeves for contracting them to grip the posts 20 and secure the member thereto.

A further object is to provide a locking device for a loose leaf binder comprising a hollow member having a pair of split clamping sleeves mounted therein, means being provided within said member for preventing the sleeves from becoming separated therefrom.

The particular object of the invention, therefore is to provide an improved locking 30 device for loose leaf binders.

Other objects of the invention will appear from the following description, and the accompanying drawings and will be pointed out in the annexed claims.

In the accompanying drawings, there has been disclosed a structure designed to carry out the various objects of the invention, but it is to be understood that the invention is not confined to the exact features shown, as 35 various changes may be made within the scope of the claims which follow.

In the accompanying drawings forming part of this specification,

Figure 1 is a perspective view of a loose 45 leaf binder showing the invention applied thereto;

Figure 2 is an enlarged detailed sectional view showing the clamping sleeves mounted in the hollow member and the means for contracting the sleeves to grip the posts secured to the complementary bar;

Figure 3 is a sectional plan view on the line 3-3 of Figure 2;

Figure 4 is a perspective view of one of 55 the clamping sleeves removed from the hollow member showing the means provided

thereon for preventing it from becoming separated from the member;

Figure 5 is a plan view partially in section showing a modified construction; and 60

Figure 6 is a cross sectional view on the line 6-6 of Figure 5.

In the selected embodiment of the invention here shown there is illustrated, for purposes of disclosure, a loose leaf binder, of 65 ordinary construction, comprising, respectively, the top and bottom covers 11 and 12 between which the usual leaves 13 are secured. The means provided for securing together the two covers consists of a bar 14 70 having a plurality of sectional posts 15 secured thereto as shown in Figure 2. These posts are of ordinary construction and need not be described in detail. The bar 14 is preferably hollow and has suitable collars 75 16 secured therein as indicated at 17, which collars are threaded to receive the threaded extension 18 of the lower post section, as shown on the right hand side of Figure 2. Each collar 16 is also provided with a counterbore 19 adapted to receive the shoulder 21 of the lower post sections for the purpose of providing a substantial connection between collar and post, and to prevent breakage of the threaded extension 18. 80

A feature of this invention resides in the novel means provided for securing the hollow member 22 to the posts 15. This member is adjustably secured to the posts so that the covers 11 and 12 and the leaves 13 interposed therebetween, may be clamped between the bar 14 and the member 22 as shown in Figure 1. The means provided for securing the hollow member 22 to the posts, consists 90 of split clamping sleeves 23 mounted in suitable apertures 24 provided in the walls thereof as shown in the upper portion of Figure 2. Each clamping sleeve 23 is split on one side as indicated at 25 in Figure 4, and has a flange 26 provided at one end 95 thereof adapted to engage the wall of the hollow member 22 when inserted in the apertures 24 thereof as shown in Figure 1. Lugs 27 are provided in the wall of each sleeve 23 adjacent the flanges 26. These lugs function to prevent the sleeves from accidentally becoming separated from the member 22 when the device is unlocked as shown in Figure 3. The sleeves 23 are made from a suitable resilient material so that when in 100 unlocked position, as shown in Figure 3, they will be expanded against the walls of

95

100

105

110

the apertures 24 provided in the hollow member 22. When thus expanded the posts 15 may readily be inserted through the sleeves as is clearly shown in Figure 3.

5 The means provided for contracting the sleeves 23 to grip the posts 15 consists of a threaded stem 28 mounted in a plug 29 fitted into one end of the hollow member 22 as shown in Figures 2 and 3. A finger grip 31 is provided upon the projecting end of the stem 28 whereby it may be conveniently rotated from the exterior of the member 22. A block 32 is received in threaded engagement with the stem 28 and has a strap 33 secured thereto which substantially encircles the two clamping sleeves 23 as particularly shown in Figure 3.

10 A U-shaped member 34 is preferably mounted between the two sections of the strap 33 adjacent the block 32 adapted to engage the adjacent sleeve 23 when the stem 28 is rotated to contract the two sleeves. This U-shaped member provides a bearing surface for the end of the threaded stem 28 when the sleeves 23 are in locked position, thereby preventing the rotation of the stem 28 from relatively rotating the sleeve 23, which might occur if the stem engaged the sleeve directly. When the hollow member 22 has been mounted upon the post 15, as shown in Figure 2, and the finger grip 31 is rotated, the block 32 will be moved toward the block 29 as a result of its threaded engagement with the stem 28, thereby causing the loop 35 adjacent the opposite end of the member 32 to engage the sleeve 23. As soon as the end of the threaded stem 28 engages the U-shaped member 34, the latter will be forced into engagement with the adjacent sleeve 23 after which continued rotation of the stem 28 will cause the two sleeves to be contracted to grip the posts 15 as shown in Figure 1. Such contracting of the sleeves 23 is effected as a result of the sleeves being clamped against the sides of the bores 24, caused by the rotation of the stem 28 tending to force the two sleeves towards each other. When it is desired to release the hollow member 22 from the posts 15, the threaded stem 28 will be rotated in the opposite direction, thereby allowing the sleeves 23 to expand to their normal position against the walls of the apertures 24, after which the member 22 may readily be removed from the posts. The sleeves 23 are preferably arranged in the position shown in Figure 3, wherein it will be noted that the slotted opening 25 in each sleeve is arranged transversely of the bar, thereby permitting the sleeves to be readily contracted when the stem 28 is rotated as above described.

15 Figures 5 and 6 illustrate a modified construction wherein clamping sleeves 36 are mounted in blocks 37 which are encircled

and engaged by the strap 38 as shown in Figure 5. Each block 37 is provided with a socket 39 adapted to receive a projection 41 provided in the wall of each sleeve 36, as shown in Figure 6. These sockets 39 and projections 41 function to prevent the sleeves 36 from becoming separated from the member 22, when the sleeves are in unlocking position. The sleeves 36 are also held against relative rotation within the locks 37 as a result of the projections 41 and sockets 39.

20 The construction of this novel locking device is such that it may be manufactured at a minimum cost. By means of the lugs 27 formed on the walls of the sleeves 23, the latter may readily be assembled in the hollow member 22 by inserting them into the apertures 24 and applying a slight pressure thereto until the sleeves contract sufficiently to permit the lugs 27 to pass through the apertures 24 in the adjacent wall of the member 22. After the lugs 27 have thus passed through the apertures 24, the sleeves will expand to their normal shape, after which the sleeves will be positively retained in the member 22 without any danger of accidentally becoming separated therefrom.

25 I claim as my invention:

1. In a loose-leaf binder the combination 95 with a bar having spaced posts mounted thereon, of a hollow clamping member having sleeves passing therethrough and adapted to receive said posts, and means within the clamping member for substantially simultaneously engaging each sleeve at one side, and contracting the same to grip said posts.

2. In a loose-leaf binder the combination 105 with a bar having spaced posts mounted thereon of a hollow clamping member having split clamping sleeves extending therethrough and normally expanded to receive the posts, and a loop element within the hollow member encircling the clamping 110 sleeves, and a threaded stem engageable with said loop element to translate the same and substantially simultaneously contract or release said sleeves.

3. In a loose-leaf binder the combination 115 with a bar having spaced posts mounted thereon and laterally extending therefrom, a hollow clamping member having normally expanded clamping sleeves centered by expansion therein, an element within the member encircling all sleeves and adapted when translated to contract the sleeves to grip the posts.

4. In a loose leaf binder the combination 125 with a bar having a post mounted therein, of a hollow member adapted to be adjustably secured to said post, an aperture in said member having a clamping sleeve mounted therein adapted to receive said post, means encircling said sleeve and having a connec- 130

tion with a threaded stem whereby said sleeve may be contracted to grip said post, said stem extending through one end of said member and having means thereon for rotating it, a flange on one end of said sleeve adapted to engage the outer surface of one of the walls of said member, and integral lugs on the wall of said sleeve adjacent said flange adapted to engage the inner surface of said wall, thereby locking said sleeve against axial movement in said member.

5. In a loose leaf binder the combination with a bar having a post mounted therein, of a hollow member adapted to be adjustably secured to said post, an aperture in said member having a clamping sleeve mounted therein adapted to receive said post, means encircling said sleeve and whereby said sleeve may be contracted to grip said post, a flange on one end of said sleeve adapted to engage the outer surface of one of the walls of said member, and integral lugs on the wall of said sleeve adjacent said flange adapted to engage the inner surface of said wall, thereby locking said sleeve against axial movement in said member.

6. A loose leaf binder comprising a bar having spaced posts thereon, a second bar having holes therein to receive said posts, means within said second bar forming a lining for said holes and through which said posts are thrust, said means being capable of contraction and expansion to grip said posts, and a device for contracting said means to clamp said posts in said holes.

7. A loose leaf binder comprising a bar having spaced posts thereon, a second bar having holes therein to receive said posts, means within said second bar forming a lining for said holes and through which said posts are thrust, said means being capable of contraction and expansion to grip said posts, and a device for contracting said means to clamp said posts in said holes, said device including a strap adapted to engage and contract said clamping means, and a threaded stem having a finger grip for operating said strap.

8. In a loose leaf binder, the combination with a bar having spaced posts mounted thereon, of a second hollow bar having holes therethrough and clamping sleeves forming linings for said holes, said holes being adapted to receive said posts, a strap mounted in said second bar and encircling said posts and clamping sleeves, a U-shaped member

engaging one of said clamping sleeves, a stem having a threaded connection with said strap for operating it to force said U-shaped member against one of said sleeves 60 and simultaneously draw said strap against the other sleeve.

9. A device of the class described comprising a binder bar having spaced openings axially parallel, a split sleeve of spring metal 65 within each opening secured therein against movement in an axial direction, said sleeve being normally expanded to center the sleeve in the opening, and means arranged to apply pressure to the sleeves in direction of their 70 alinement.

10. A device of the class described comprising a binder bar having spaced openings, axially parallel, a split sleeve of spring metal within each opening secured therein against 75 movement in an axial direction, said sleeve being normally expanded to center the sleeve in the opening, and means arranged to apply pressure laterally against each sleeve in direction and against one side only of the 80 sleeves.

11. A device of the class described comprising a binder bar having spaced openings, axially parallel, a split sleeve of spring metal within each opening secured therein 85 against movement in an axial direction, said sleeve being normally expanded to center the sleeve in the opening, and means arranged upon the bar to apply pressure against the sleeves, from one side of each. 90

12. A device of the class described comprising a bar having spaced posts, a second bar having openings, and split sleeves within the openings, normally expanded to center the sleeves within the openings to register 95 with and normally slide upon the posts, and means associated with the sleeves and bar to apply pressure to one side of each sleeve.

13. A device of the class described comprising a bar having spaced posts, a second 100 bar having openings, and split sleeves within the openings, normally expanded to center the sleeves within the openings to register with and normally slide upon the posts and means associated with the sleeves and bar to apply pressure to one side of each sleeve, said sleeves passing entirely through the bar and secured therewith against movement in an axial direction. 105

In witness whereof, I have hereunto set 110 my hand this 14th day of April, 1926.

BERNARD W. JAPS.
